US00D793953S

(12) **United States Design Patent** (10) **Patent No.:** **US D793,953 S**
(45) **Date of Patent:** **** Aug. 8, 2017**

(54) **BATTERY**

(71) Applicant: **Techtronic Industries Co. Ltd.**, Tsuen Wan, New Territories (HK)

(72) Inventors: **Douglas Ritterling**, Chagrin Falls, OH (US); **Shane Glasgow**, Reminderville, OH (US)

(73) Assignee: **Techtronic Industries Co. Ltd.**, Tsuen Wan, New Territories (HK)

(**) Term: **15 Years**

(21) Appl. No.: **29/581,581**

(22) Filed: **Oct. 20, 2016**

Related U.S. Application Data

(63) Continuation of application No. 29/528,139, filed on May 26, 2015, now Pat. No. Des. 772,806.

(57) **CLAIM**

We claim the ornamental design for a battery, as shown and described.

DESCRIPTION

FIG. 1 is a perspective view of a battery;

FIG. 2 is a back side view of the battery shown in FIG. 1.

FIG. 3 is a front side view of the battery shown in FIG. 1.

FIG. 4 is a right side view of the battery shown in FIG. 1.

FIG. 5 is a left side view of the battery shown in FIG. 1.

FIG. 6 is a bottom side view of the battery shown in FIG. 1; and,

FIG. 7 is a top side view of the battery shown in FIG. 1.

The elements shown in dashed lines are included for the purpose of illustrating environment and form no part of the claimed design.
